UNITED STATES PATENT OFFICE.

TOWNSEND G. TREADWAY, OF BRISTOL, CONNECTICUT, ASSIGNOR TO THE HORTON MANUFACTURING COMPANY, OF BRISTOL, CONNECTICUT, A CORPORATION OF CONNECTICUT.

GOLF-CLUB SHAFT.

Application filed July 14, 1922. Serial No. 574,951.

To all whom it may concern:

Be it known that I, TOWNSEND G. TREADWAY, a citizen of the United States, residing at Bristol, in the county of Hartford and 5 State of Connecticut, have invented certain new and useful Improvements in Golf-Club Shafts; and I do hereby declare the following to be a full, clear, and exact description of the same, reference being had to the 10 accompanying drawings, forming a part of this specification.

This invention relates to golf clubs and more particularly to golf clubs provided with a hollow, or tubular, metallic shaft.

15 An object of the invention is to provide a golf club with a tubular metallic shaft that can be united at its meeting edges by a welded seam extending throughout its length and that can also be reinforced 20 throughout its length from its interior by a wooden core or filler.

A further object is to provide a tubular metallic shaft that will possess torsion or be capable of twisting under the strains 25 placed upon it by the impact of the club head on the ball without liability of fracturing the shaft, and while this possibility of the shaft being broken under such conditions is preferably eliminated by reinforcing the shaft from both its interior and 30 exterior, the same result can also be obtained with more or less the same degree of safety with one or the other of said reinforcing means eliminated.

35 In the accompanying drawings—

Figure 1 is a side view, partly in section and partly in elevation, of a golf club embodying the present improvements;

Fig. 2 is a sectional view of the shaft; and

40 Fig. 3 is a detail view of that portion of the shaft which is provided with means for permitting the shaft to twist when a blow is delivered with the club;

Fig. 4 is a cross sectional view;

45 Figs. 5 and 6 are additional detail views showing other locations in the shaft for the means for permitting torsion or twisting of the latter.

50 While the present invention is equally applicable to practically all types of golf clubs, it is shown, in the present instance, embodied in the club known as the mid-iron.

A club of this type has an all metallic head 10 formed at its rear end with an upwardly extending sleeve like shank or hosel 11 which has a socket therein for the reception and attachment of the shaft 12. Shaft 12 is also made entirely of metal, being made tubular or hollow and tapered somewhat 60 from its handle end to the end which is secured in the hosel or head and to strengthen said shaft to withstand the strains placed upon it, it is reinforced throughout its length by a wooden core or filler 13. Said 65 core is of comparatively light material, such as balsa wood, and is tapered similarly to the shaft 12 whereby it will have a wedging action and make a close fit when inserted in said shaft although it and the shaft are 70 firmly secured together, as well as in the head or hosel, by a transverse rivet 14 extending through the hosel, shaft and core.

It has heretofore been somewhat difficult to provide a metallic hollow shaft that would 75 successfully stand up under ordinary usage and in the present invention, to meet the requirements as to strength, the shaft 12 is made from an imperforate (except for a feature hereinafter described) sheet of metal 80 bent into tubular form. The meeting edges of the tube are welded together and form a seam 15 extending throughout the length of the tube or shaft and to accommodate the increased thickness of the shaft at said 85 seam the wooden core or filler 13 is grooved longitudinally, as at 16. In this way, the exterior of the shaft is free from ridges and the core 13 fits the shaft snugly at all points.

The ordinary steel tubular shaft has been 90 found objectionable for the reason that it does not possess torsion or the quality of twisting when the ball is struck and the present invention seeks to overcome this deficiency by providing said shaft with one 95 or more slots that may be located at any of several points in the length of the shaft whereby the shaft may torsion under impact. In carrying out this idea, the steel shaft is, of course, somewhat weakened by 100 the slots therein and for this reason the shaft is reinforced against collapse or fracture.

The preferred arrangement is shown in Figs. 1, 2 and 3 and consists of a plurality 105 of longitudinally extending slots 17 (usually

three placed equi-distantly around the shaft) located adjacent the lower end of the shaft where they will be surrounded by the hosel 11. With this arrangement, the slotted portion 5 of the shaft is supported from its interior by the wooden core 13 and from its exterior by the sleeve like hosel 11. If desired, however, the same results can be obtained by locating the slots at a point where 10 they will be enclosed by the handle 18, as indicated at 17^a; or if desired the slotted portion need be given support from one side only as by locating the slots 17^b at any point intermediate the handle 18 and hosel 15 11, in which case said slotted portion will be reinforced only from its interior by the core 13. With any one of these arrangements it will be found that the shaft is capable of 20 torsion or twisting perfectly but, due to the reinforcing effect afforded by either the core and hosel, the core and handle, or the core alone, as the case may be, the weakened portion adjacent the slots will still possess the necessary strength to prevent its breakage 25 under the most trying usage. In this preferred construction, the metal shaft 12 is circular in cross-section, having a smooth exterior surface, and the wooden core 13 is also circular in cross-section, making a snug fit 30 in the shaft throughout the length of the latter. With this arrangement the shaft is amply reinforced by the filler and the use of the reinforcing filler does not necessitate the abandonment of the circular shaft now 35 generally used and the use, in lieu thereof, of a shaft of unusual or disagreeable cross-section or appearance. Furthermore, the entire metal shaft is filled by core 13, leaving no hollow portions that may easily be 40 dented or otherwise injured.

What is claimed is:

1. In a golf club, the combination of the head, a hollow metallic shaft extending into said head and having a longitudinally extending slits intermediate its ends to permit 45 twisting of the shaft, said slit being located within the club head whereby the slotted portion of the shaft is reinforced transversely by the head, and means for secur-

ing the shaft in the head, said slit being spaced from said securing means.

2. In a golf club, the combination of the head, a hollow metallic shaft, said shaft having a longitudinal slit intermediate its ends, and a reinforcing sleeve secured to the shaft adjacent the slotted portion to prevent fracture of the shaft at that point by strains placed on the shaft transversely thereof, said slotted portion of the shaft permitting said shaft to torsion under impact. 60

3. In a golf club, the combination of the head, a hollow metallic shaft secured in the head, said shaft having a longitudinal slit intermediate its ends and a wooden strengthening core in the shaft adjacent the slotted portion, said core being removable with said shaft and said slotted portion of the shaft permitting said shaft to torsion under impact. 65

4. In a golf club, the combination of the head having a sleeve-like socket and a hollow metallic shaft secured in the socket, said shaft having a longitudinal slit therein spaced from the shaft ends and surrounded by the sleeve formed by the socket, said 75 slotted intermediate portion of the shaft permitting the shaft to torsion under impact. 70

5. In a golf club, the combination of the head, a hollow metallic shaft, means for securing the shaft in the head, said shaft having a longitudinal slit intermediate its ends, the slotted portion of said shaft being spaced from the securing means and located within the head whereby it is reinforced from its exterior by the head and a filler within the 85 shaft for reinforcing the slotted portion of the shaft from the interior of said shaft. 80

6. In a golf club, the combination of a head, a hollow metallic shaft extending into said head and having a longitudinally extending slit intermediate its ends to permit torsioning of the shaft, said slit being located within the club head whereby the slotted portion of the shaft is reinforced 95 transversely by the head, and means for securing the shaft in the head. 90

TOWNSEND G. TREADWAY.
